UNITED STATES PATENT OFFICE.

JAKOB MANZ, OF LONDON, ENGLAND, ASSIGNOR OF ONE-HALF TO WILLIAM ERNEST DEVESON, OF LONDON, ENGLAND.

PETROL OR SPIRIT LIGHTER FOR CIGARS AND OTHER OBJECTS.

1,401,344.

Specification of Letters Patent. Patented Dec. 27, 1921.

Application filed August 20, 1919. Serial No. 318,703.

(GRANTED UNDER THE PROVISIONS OF THE ACT OF MARCH 3, 1921, 41 STAT. L., 1313.)

To all whom it may concern:

Be it known that I, JAKOB MANZ, mechanician, a citizen of the Swiss Confederation, residing at London, England, have invented certain new and useful Improvements in Petrol or Spirit Lighters for Cigars and other Objects, of which the following is a specification.

This invention relates to sparking igniters, which comprise a fuel receptacle provided with an opening and containing an absorbent material, such as felt impregnated with a volatile combustible oil, a striking pin provided with an absorbent wad and adapted to enter the receptacle through said opening, the said receptacle and striking pin being connected with spark producing elements adapted to coöperate with each other. The spark producing element on the striking pin is usually made of hard metal and that on the receptacle of flint or a pyrophoric alloy. The fuel receptacle may contain a perforated tube extending inwardly from the said opening and adapted to receive the striking pin. In a known instrument of this kind the fuel receptacle is mounted on a base, and the spark producing element is mounted on the said base and consists of a long block or strip held in a groove provided with outwardly extending flanges, the part supporting the said block thus forming an element separate from the receptacle, but connected with the same by means of the said base and the said flanges being relatively narrow.

The present invention has for its object to simplify the construction and increase the utility of such instruments.

For this purpose the fuel receptacle consists of a specially shaped box, preferably made of sheet metal, the front of said box being formed by a right hand and a left-hand half converging symmetrically inward toward the center line, so as to form an obtuse angle in the apex of which is situated a narrow groove adapted to contain a strip of sparking material which is inserted into the groove.

In the accompanying drawing Figure 1 is a front view of an example embodying my invention;

Fig. 2 is an axial section through the reservoir holding the absorbent material, along line B—B of Fig. 3.

Fig. 3 is a transverse section of same, along line A—A of Fig. 2,

Figs. 4 and 5 represent modifications.

Fig. 6 shows on a larger scale an example of a striking pin suitable for use with my improvements.

In this drawing:

a indicates a sheet metal reservoir or casing provided with a flange a¹ having holes a² for screwing it to a wall,

b indicates a piece of absorbent material filling the interior of the reservoir a and provided with an axial opening b¹, and b² is a metallic guide tube or lining fixed to the top of the receptacle by means of a flange b³,

c a striking pin which is normally suspended in the tube by means of a head c¹ resting on the top of the casing, and which has a steel core c² surrounded on a part of its length by an asbestos tuft c³ held by a metallic clip c⁴ secured to the pin c. The said head c¹ forms with the opening in the top of the casing an air-tight joint, for which purpose it is preferably made conical, as shown. The guide tube shown in Fig. 2 may be solid, or it may have lateral perforations. The striking pin extends substantially below the guide tube, so as to touch the lower part of the felt.

In the modification represented by Fig. 4 the guide tube is longer and must be perforated, so that the petrol reaches the asbestos through the perforations of the tube.

According to the modification indicated by Fig. 5 the guide tube b² is omitted, and the asbestos of the striking pin c is in direct contact with the sides of the central opening.

To facilitate the construction of a hermetically closed reservoir the latter is composed of two main parts, viz. the casing open at the back, and the base plate forming the flange a¹. The felt is introduced into the casing from the open back and then the casing soldered on the base plate.

What I claim is:

In an igniting instrument of the kind described, a fuel reservoir adapted to be mounted on a stationary base and having a face composed of right and a left half converging symmetrically toward the center line and having in the apex of the angle thus formed a strip of frictional igniting material fixed in the said face, substantially as described.

In testimony whereof I have hereunto set my hand.

JAKOB MANZ.
